NOVELTY AND AMUSEMENT DEVICE

William A. McMillan, Los Angeles, Calif., assignor to
H. Fishlove & Co., Chicago, Ill.

Filed Apr. 29, 1970, Ser. No. 22,706

Term of patent 14 years

Int. Cl. D21—04

U.S. Cl. D34—15

FIG. 1

FIG. 4

FIG. 2

FIG. 3

FIG. 5

FIG. 1 is a side elevational view of a novelty and amusement device showing my design.

FIG. 2 is a top plan view thereof.

FIG. 3 is a bottom plan view thereof, with the rear collar slid forward to expose the opening for filling the device.

FIG. 4 is a front view, and

FIG. 5 is a rear view.

I claim:

The ornamental design for a novelty and amusement device, as shown and described.
